(57) **CLAIM**

The ornamental design for a pet toy, as shown and described.

DESCRIPTION

FIG. 1 is a top perspective view of a pet toy, showing my new design;

FIG. 2 is a bottom perspective view thereof, illustrated in a condition of use;

FIG. 3 is a left-side elevational view thereof, the right-side elevational view, front elevational view, and rear elevational view all being identical thereto;

FIG. 4 is a top plan view thereof;

FIG. 5 is a bottom plan view thereof;

FIG. 6 is a cross-sectional view thereof, taken along line 6-6 of FIG. 3; and,

FIG. 7 is a cross-sectional view thereof, taken along line 7-7 of FIG. 4.

The broken lines in FIG. 2 depict environmental structure that forms no part of the claimed design.

1 Claim, 7 Drawing Sheets
